UNITED STATES PATENT OFFICE

105,330

DESIGN FOR A STATUETTE OR SIMILAR ARTICLE

Adolph J. Hamrin, Minneapolis, Minn.

Application December 14, 1936, Serial No. 66,509

Term of patent 14 years

To all whom it may concern:

Be it known that I, Adolph J. Hamrin, a subject of the King of Sweden, residing at Minneapolis, Hennepin County, and State of Minnesota, have invented a new, original, and ornamental Design for a Statuette or Similar Article, of which the following is a specification, reference being had to the accompanying drawing forming a part thereof, wherein,

Fig. 1 is a side elevational view, slightly in perspective, of a statuette or similar article showing my new design; and

Fig. 2 is a front view of the same.

I claim:

The ornamental design for a statuette or similar article, substantially as shown.

ADOLPH J. HAMRIN.
